UNITED STATES PATENT OFFICE

169,127

STOCKING

Joseph C. Cobert, Concord, N. C., assignor to Hugh Grey Hosiery Company, Concord, N. C., a corporation of North Carolina

Application February 19, 1952, Serial No. 18,592

Term of patent 14 years

(Cl. D47—7)

To all whom it may concern:

Be it known that I, Joseph C. Cobert, a citizen of the United States, residing at Concord, North Carolina, have invented a new, original, and ornamental Design for a Stocking, of which the following is a specification, reference being had to the accompanying drawing, forming a part hereof.

The characteristic feature of my design resides in the combination on the stocking disclosed of the specific angled cap formed in the contrasting border at the top of the heel splice, as shown.

I claim:

The ornamental design for a stocking, as shown and described.

JOSEPH C. COBERT.
